CLAIM

The ornamental design for a spacer device for dispensing inhalant medication, as shown and described.

DESCRIPTION

FIG. 1 is a side elevational view of a spacer device for dispensing inhalant medication showing my new design, the view from the opposite side being a mirror image;

FIG. 2 is a top plan view thereof;

FIG. 3 is a bottom plan view thereof;

FIG. 4 is a back elevational view thereof; and,

FIG. 5 is a front elevational view thereof.
